The ornamental design for a patient trunks garment, as shown.

DESCRIPTION

FIG. 1 is a front view of a patient trunks garment showing my new design, with a portion of a front panel portion of the garment shown unsnapped and folded back to show portions of a rear panel, and with said front panel shown partially unsnapped from said rear panel;

FIG. 2 is a rear view of said patient trunks garment;

FIG. 3 is a left-side view of said garment;

FIG. 4 is a right-side view of said garment;

FIG. 5 is a top view of said garment; and,

FIG. 6 is a bottom view of said garment.
